FIG. 5.

INVENTOR:

Engelbert Biber

By Chas. H. Luther

ATTORNEY:

UNITED STATES PATENT OFFICE.

ENGELBERT BIBER, OF PROVIDENCE, RHODE ISLAND.

TOBACCO BURNER FOR PIPES.

Application filed April 7, 1927. Serial No. 181,862.

My invention has reference to an improvement in tobacco pipes and more particularly to an improvement in an auxiliary device adapted to be inserted into the bowl of a 5 tobacco pipe.

The object of my invention is to provide the bowl of a tobacco pipe with a device adapted to give a dry and cool smoke, when the pipe is smoked.

10 Another object of my invention is to provide a tobacco pipe with a device having a movable member that assists in packing the tobacco in the device and that will hold the tobacco away from the bottom of the pipe bowl, thereby forming a chamber in the device below the tobacco.

Another object of my invention is to provide the bowl of a tobacco pipe with a device adapted to materially assist the burning 20 of the tobacco, whereby the tobacco is completely burnt up, thereby leaving no residue of tobacco or heel in the pipe, in smoking the pipe.

Further objects of my invention are to improve and simplify the construction of such a device, whereby tobacco pipes are greatly improved and the cost of manufacturing the device is reduced to a minimum.

30 My invention consists in the peculiar and novel construction of an auxiliary tobacco burning device for tobacco pipes, said device having details of construction, as will be more fully set forth hereinafter and claimed.

Figure 1 is a top plan view of a tobacco 35 pipe provided with my improved tobacco burning device.

Figure 2 is a side view of the pipe with the pipe bowl in section and showing my improved tobacco burning device in full lines, 40 in the bowl of the pipe.

Figure 3 is an enlarged vertical sectional view of the tobacco burning device.

Figure 4 is an enlarged top plan view of the movable member of the device, and

45 Figure 5 is an enlarged vertical sectional view of the movable member of the device, taken on line 5, 5, of Figure 4.

In the drawing 1 indicates a tobacco 50 smoking pipe and 2 my improved tobacco burning device for tobacco smoking pipes.

The tobacco pipe 1 has the usual bowl 3 in which is a tobacco cavity 4 having the usual side walls 5, 5, and bottom 6. The pipe stem 7 has the usual smoke duct 8, entering

the bottom 6 of the tobacco cavity 4, as 55 shown in Figure 2.

My improved tobacco burning device 2 consists essentially of a thin metal hollow body member 9 and a movable tobacco packing and chamber forming member 10. 60

The body member 9 is circular in cross section and has an open top 11 and tapered sides 12, 12, merging into a rounded bottom 13 in which is a vertical central stem opening 14. In the tapered sides 12, 12, are preferably six vertical slots 15, and secured at the open top 11 are small oppositely disposed and outwardly extending lugs 16, 16. Each lug 16 is formed of a flat strip of metal and bent around the open top 11 through a 70 slot 15, as shown in Figure 3.

The movable tobacco packing and chamber forming member 10 consists of a round stem 17 which extends inward through the stem opening 14 in the body member 9. Secured to the top of the stem 17 is a flat disk 18 having preferably six radial arms 19, 19, which extend outward through the slots 15, 15, in the body member 9, and on the lower end of the stem 17 is a nut 20 secured to the 80 end of the stem, as shown in Figures 4 and 5. When the device is out of the pipe bowl for filling with tobacco, the disk 18 is normally down near the bottom 13 of the device, as shown in Figure 3. 85

When in use my improved tobacco burning device 2 is preferably first filled loosely with tobacco, inserted into the pipe bowl and then pressed downward into the pipe bowl with a finger on the tobacco. The small lugs 90 16, 16, now rest on the top rim of the pipe bowl and the lower end of the stem 17 contacting with the bottom 6 of the pipe bowl forces the disk 18 upwards, thus giving the required amount of packing to the tobacco. The disk 18 is now in the position, as shown in Figure 2, and with the sides 12, 12, and the bottom 13 of the device, forms a moisture proof chamber 21 below the tobacco. The device when inserted into the pipe bowl 100 also forms a circular side chamber 22, between the device and the circular inside walls 5, 5, of the pipe bowl and a moisture collecting chamber 23 in the bottom 6 of the pipe bowl, below the bottom 13 of the device, as shown in Figure 2.

A tobacco pipe provided with my improved tobacco burner gives a dry cool

smoke, dry because the tobacco is kept entirely away from the bottom of the pipe bowl where moisture collects in smoking the pipe and cool, as a predetermined amount of air is drawn into the pipe through the circular side chamber 22, in the pipe bowl. Also as the tobacco is kept dry it will now burn through the slots 15, 15, in the sides 12, 12, of the device to a clean ash, thereby leaving no tobacco residue in the bowl of the pipe.

Having thus described my invention I claim as new:—

1. In a device of the nature described, a thin hollow body member having sides, an open top and a closed bottom in which is a stem opening, said sides having a plurality of slots, a movable member having a stem extending through the stem opening in the body member, a disk on the inner end of the stem, said disk having arms extending through the slots in the body member, for the purpose as described.
2. In a device of the nature described, a thin hollow body member having sides in which are a series of slots, an open top and a closed bottom, having a stem opening, a movable member having a stem extending through the stem opening in the body member, a disk on the inner end of the stem, said disk having arms extending outwardly through the slots in the body member and small lugs at the top of the body member, for the purpose as described.
3. In a device of the nature described, a thin metal hollow body member having tapered sides in which are a series of slots, an open top and a closed bottom having a stem opening, a movable member having a stem extending inwards through the stem opening in the body member, a disk on the inner end

of the stem and having radial arms extending through the slots in the body member, for the purpose as described.

4. In a device of the nature described, a thin metal hollow body member having tapered sides in which are a series of longitudinal slots, an open top on which are outwardly extending small lugs, and a closed bottom in which is a central stem opening, a movable member having a stem, extending inwards through the stem opening in the bottom of the body member, a flat disk on the inner end of the stem and having radial arms extending outward through the slots in the body member, for the purpose as described.

5. In a device of the nature described, a thin metal hollow body member, circular in cross section and having an open top on which are small outwardly extending lugs, tapered sides in which are a plurality of longitudinal slots and a closed rounded bottom in which is a central stem opening, a movable member having a stem extending into the body member through the stem opening, a flat disk on the inner end of the stem and having radial arms extending outward through the slots in the body member and a nut on the outer end of the stem, whereby when the device is in use in the bowl of a tobacco pipe, a circular chamber is formed intermediate the device and the inner walls of the pipe bowl, a chamber is formed intermediate the disk on the movable member and the bottom of the body member and a chamber is formed in the bottom of the pipe bowl below the bottom of the body member, for the purpose as described.

In testimony whereof, I have signed my name to this specification.

ENGELBERT BIBER.
